United States Patent Office

Des. 180,786
Patented Aug. 13, 1957

180,786

COMPASS CASING

Walter E. Hull, Trumbull County, Ohio

Application December 15, 1955, Serial No. 39,343

Term of patent 14 years

(Cl. D52—1)

Fig. 1

Fig. 2

Fig. 3

Figure 1 is a side elevational view of a compass casing showing my new design,

Figure 2 is a front elevational view thereof, and

Figure 3 is a top plan view of the design.

The dominant features of the design reside in the portions shown in full lines.

I claim:

The ornamental design for a compass casing, substantially as shown and described.
